UNITED STATES PATENT OFFICE.

WILLIAM B. MOORE, OF CHICAGO, ILLINOIS.

LOCK.

SPECIFICATION forming part of Letters Patent No. 664,422, dated December 25, 1900.

Application filed November 15, 1899. Serial No. 737,141. (No model.)

To all whom it may concern:

Be it known that I, WILLIAM B. MOORE, a citizen of the United States, residing at Chicago, Illinois, have invented Improvements 5 in Mortise-Locks, of which the following is a specification.

My invention relates generally to improvements in mortise door-locks; and the primary objects of my improvements are to provide a 10 lock of this character which may be readily converted from a right-hand to a left-hand lock, thus avoiding the necessity of making one pattern for right-hand doors and an another pattern for left-hand doors; to provide 15 an invertible as well as a reversible lock in the same pattern; to provide a lock which may be changed from a cylinder-lock to a key or tumbler lock; to provide a lock which when used as a cylinder-lock the cylinder will be 20 above the door-knob and when used as a key-lock the keyhole will be below the knob; to provide a lock in which the latch or bolt locking parts operate by gravity; to provide a lock in which the latch or bolt locking parts operate 25 by gravity equally as well when the lock is inverted as when in its normal position; to provide a lock in which the latch or bolt will be locked automatically by the closing of the door, and to provide a lock in which the latch 30 also performs the function of a bolt.

In carrying out the foregoing objects and others of economy of construction and simplicity of operation I provide a reversible front or face plate in order that my lock may 35 be used on doors having beveled edges and reversible operative parts of novel construction and arrangement, as will be described hereinafter and as illustrated in the accompanying drawings, which form a part of this application for patent, and in which—

Figure 1 is a side elevation of my improved lock in the cylinder-lock form, the cap-plate being removed to show the operative parts, which are in their normal position taken 45 when the door to which the lock is applied is open. Fig. 2 is a similar view, the parts being shown in the position taken when the door is closed. Fig. 3 is an elevation of the combination latch-bolt and the locking-plate 50 which is pivoted thereto. Fig. 4 is an elevation of the reverse side of the parts shown in Fig. 3. Fig. 5 is a cross-section of the front

or face plate and the adjusting-plate applied thereto. Fig. 6 is an elevation of the lock when used as a key-lock, the method of applying the keyhole-plate being shown. Fig. 7 is an elevation of the lock when used in the cylinder-lock form. Fig. 8 is a rear elevation of a sliding bar for releasing the locking-plate; Fig. 9, a detail of the key-plate; Fig. 10, a detail of the cylinder.

Referring to the drawings, 1 represents a lock-case, to which are secured a cap-plate 1^a and a face-plate or front 2. In order to apply my reversible lock to a beveled-edge door, it is 55 necessary to provide a reversible front, and this I accomplish by interposing between the front and the edge of the case a beveled plate 3, such plate being removably attached, so that it may be discarded if the lock is applied 60 to a door having a straight edge instead of a beveled edge. The inner side of the front has formed thereon studs 2^a, the ends of which are threaded to receive suitable nuts, and these studs pass through elongated slots 3^a in 65 the plate 3 and also through suitable holes formed in the lugs 7 upon the lock-case, so that by screwing up the nuts the front beveled plate and case are secured together. In 70 order to change the angle of the front, it is 75 only necessary to unscrew the nuts, remove the front, turn over the plate 3, and then restore the parts to their former position.

When used in the cylinder form, I mount 80 on the square shank or spindle f of the cylinder F a disk or hub A, in which a square opening a' is formed for the spindle f, thus 85 effecting the rotation of the hub with the cylinder. Extending from the periphery of the hub A is an arm a, which is so positioned that 90 upon the forward rotation of the hub the said arm will strike against and push rearwardly the end d' of the lever D, the lower portion of which is pivoted on a stud 5 upon the case and is provided with an angular extension d. 95 The same movement of the lever D is also obtained through the medium of the hubs H H', which are mounted through their central perforations h' on the square shank of the door-knob K', which is of the usual form. The 100 hubs have shoulders h^a formed thereon, which abut against shoulders d^b on the lever D, thus operating the lever when the hubs (or either of them) are rotated forwardly upon their axis.

The hub H has a notch h in its periphery at a point directly opposite the inner end i of the hub-locking bolt I. This bolt I, together with its companion bolt I', is pivoted to a lever J, mounted on a stud 6 upon the case, extends through the plate 3 and the front, and by being pushed backward or forward serves to lock or release the hub H, constituting the well-known method of preventing the unlatching 10 of the door by turning the outside knob. As this feature of my lock is of the usual construction and operation, it need not be described in detail in this connection, it forming no part of the invention.

15 A spring 12, having one end secured against the lug 7 and bent over the pin 6, has its other end bearing against the end d of the lever D, so that the normal tension of the spring is to throw the opposite end of the lever forwardly. A spring 13, secured to the lugs 8 and bent to form a bowed portion near its center, bears against the lower end of the lever J and retains it in its adjusted positions in a well-known manner.

20 25 To the under side of the lever D, near its end d', is fixed a pin d² in position to engage the slot b³ in the latch-bolt B and the slot c³ in the locking-plate C, said pin normally pressing against the forward side of said slots, 30 and thus forcing the latch-bolt B forwardly.

The latch-bolt B has the usual beveled end b extending through suitable openings in the plate 3 and the front and is adapted to engage the socket in the strike when the door is closed. The latch-bolt is made reversible and is formed with a square slot b³ near its rear end and an oval slot b² just forward of the center. A pin b' extends through the latch-bolt at a point just back of the shoulder b⁴ formed by the end b, which is thicker than the body of the latch-bolt, said pin projecting equally on each side of the latter. Pivotally mounted on the lower end of the pin b' is a gravity locking-plate C, which in the form shown serves also as a tumbler and fits snugly to the under side of the latch-bolt. In the upper side of the locking-plate C a pin c³ is fixed in position to fit loosely in the oval slot b² in the latch-bolt, and near the rear end of 45 said plate is formed a triangular slot c⁴, which when the locking-plate and the latch-bolt are in position comes directly under the square slot b³ in the latter and surrounds the pin d² in the lever D. At right angles with the body 50 of the locking-plate an extension c is formed, in the rear side of which is a notch c', and in the lower rear corner a lug or shoulder c² is formed with a slanting edge toward the front of the case, said lug serving as a stop for the 55 key when one is used.

Secured to the inner side of the case at points just above and below the upper and lower edges of the latch-bolt B are elongated lugs 4, which serve as guides for the said latch-bolt when it is pushed inwardly and as stops for the locking-plate when it falls below the plane of either of said lugs.

When the pin c³ is directly in the center of the oval slot b², it, the pin b', and the pin d² will be in the same line, and the latch-bolt 70 and the locking-plate will move in the same horizontal plane and are normally held in this position by the bar E. The latter forms a part of what I term a "locking" latch-bar. It has a beveled front end e, which projects through 75 suitable openings in the plate 3 and the front 2 and is formed with steps or shoulders e⁴ on the upper and lower sides, on one of which the lower edge of the latch-bolt rests and is thereby supported in its sliding movement. 80 At each end of the bar E is a notch e' e², the former embracing the post 10 of the case and the latter partially surrounding the pin c³ of the plate C. A portion of the bar is cut away, leaving a shoulder E', against which bears 85 one end of a spring e³, which is wound about a post 10 and has its opposite end bearing against the bottom of the case, thus causing the normal tension of said spring to bear against said shoulder and shoot the bar e outwardly, which position will be maintained so long as the door is opened. In this position the bar E by its forward pressure upon the pin c³ and by the sides of its notch e² will furnish a support for the locking-plate and maintain it in its horizontal position. When the bar E is retracted by the pushing inwardly of its forward end e, the notch e² leaves the pin c³, thus releasing the locking-plate, so that it will fall by gravity the distance permitted by 100 the pin d², and when it has so fallen the notch c' will be below the lower lug 4 and the rear end of the locking-plate will strike against 105 said lug when an attempt is made to retract the latch-bolt, thus effectively locking the latter until the latch-bolt is raised to its former and normal position. This return of the locking-plate to its horizontal position in line with the latch-bolt may be accomplished in two different ways. If a key be used, the 110 locking-plate may be raised until its notch c' registers with the lug 4, and the same result would be accomplished if several plates were used, each having a suitable notch to receive the lug 4. The plate will also be raised by 115 turning the lever D backwardly, thus causing the pin d² to bear against the upper sloping edge of the slot c⁴ in said plate and continuing the movement until the notch c' registers with the adjacent lug 4 and the pin strikes 120 against the rear wall of the slot b³, and thus retracts the latch-bolt B. When the door is opened, the latch-bolt will be shot forward by the action of the spring 12 on the lever D and also by the action of the spring e³ on the bar 125 E, which will also be shot forward, the notch e² returning to its normal position about the pin c³. When the door is closed against the strike S, the latch-bolt end b will enter the socket provided therefor; but as no opening 130 will be provided for the end e of the bar E the latter will be pushed inwardly, and when in such retracted position the operation above described will take place.

If it should be desired to operate the lock by means of a key in place of a cylinder, I remove the cylinder and the hub A and apply the key-plate K, ways k being provided therefor in the back and cap of the case. Said plate may be held in position on the case by being sprung into the ways or by a screw k' passing through a suitable opening in the bottom of the plate and into a threaded opening in the bottom of the case. By inserting a suitable key and turning it until it strikes against the lower edge of the plate C the latter will be raised until the notch c' registers with the lug 4, and by continuing the movement of the key it will impinge on the shoulder c², and thus retract the plate and with it the latch-bolt B, thus unlocking the door, which has been automatically locked by the closing thereof, as heretofore described.

Should it be desired to use the lock in the cylinder-lock form, the key-plate K is removed, and the cylinder, with the hub A mounted on its spindle f, is inserted in the case, the arm a being in position opposite the end d' of the lever D, so that upon the rotation of the cylinder the lever D will be operated in the same manner as by the hub H, which has been described. The casing of the cylinder, which is of the usual form, will be fitted to the opening f² in the cap-plate.

I am aware that reversible and gravity locks are common; but it will be noted that my improved lock, while possessing the gravity features, is invertible as well as reversible, thus providing that when used as a key-lock the keyhole be below the door-knob, and when used as a cylinder-lock the cylinder containing the keyhole be above the door-knob in the usual manner. I am aware that reversible latches are common; but it should be observed that my reversible latch performs the function of the usual bolt employed in most locks in addition to the latch. I am aware also that locking-plates have been used which work by gravity, but the same have been pivoted to the lock-case, while in my lock the said plate is pivoted to the latch-bolt. Attention is invited to the peculiar construction of the hub A, in that both sides are alike, thus permitting the application of the cylinder from either side of the lock.

Having thus described my invention, what I claim as new, and desire to secure by Letters Patent, is—

1. In a lock, a sliding latch-bolt and invertible means for locking same in its projected position in connection with stops secured to the lock-case, said means being pivotally secured to said latch-bolt and operating by gravity to lock the latch-bolt in said position.

2. In a lock, a sliding latch-bolt, one or more invertible locking-plates pivoted to the latch-bolt and operating by gravity in connection with stops or lugs secured to the lock-case, to lock the latch-bolt in its projected position, and means for raising and retracting said locking plate or plates.

3. In a lock, a sliding latch-bolt, gravity-operated locking plate or plates pivoted to said latch-bolt, stops or lugs secured to the lock-case to engage with said locking-plates, means independent of the latch-bolt for supporting said locking-plates, said means being also adapted to release said plates.

4. In a lock, a sliding latch-bolt, one or more locking-plates pivoted to the latch-bolt and adapted to lock same in its projected position, means independent of the latch-bolt for supporting and releasing said plate or plates, said means being automatically operated by the opening and closing of the door to which the lock is attached.

5. In a lock, a sliding latch-bolt, one or more locking-plates pivoted to the latch-bolt and adapted in connection with stops on the lock-case to lock same in its projected position, means independent of the latch-bolt for supporting and releasing said locking plate or plates, and means for raising and retracting said locking plate or plates.

6. In a lock, a sliding latch-bolt, a gravity-operated locking - plate pivoted thereto, a knob-operated lever adapted to raise said locking-plate and retract and project said latch - bolt, and means independent of the latch-bolt for supporting and releasing said locking-plate.

7. In a lock, a sliding latch-bolt, a gravity-operated locking - plate pivoted thereto, a knob-operated lever adapted to raise said locking-plate and retract and project said latch - bolt, and means independent of the latch-bolt for supporting and releasing said locking-plate, said means being adapted to be automatically operated by the opening and closing of the door to which the lock is secured.

8. In a lock, a sliding latch-bolt, a locking plate or plates pivoted thereto and having portions adapted to be engaged by the wards of a key, means for sliding said latch-bolt, and means independent of the latch-bolt for supporting and releasing said locking plate or plates.

9. In a lock, a sliding latch-bolt, a locking-plate pivoted thereto, and having portions adapted to be engaged by the wards of a key, and having a slot therein, a knob-operated lever having a portion adapted to engage said slot, means for sliding said latch-bolt, and means for supporting and releasing said locking-plate.

10. In a lock, a sliding latch-bolt, a locking-plate pivoted thereto, adapted to operate by gravity, having a portion adapted to be engaged by the wards of a key and having a slot therein, a knob-operated lever having a portion adapted to engage said slot, and means for supporting and releasing said locking-plate, said means being automatically operated by the opening and closing of the door, as set forth.

11. In a lock of the character described, a removable key-plate adapted to embrace the

lock-case, the latter having ways formed therein to receive the same, as set forth.

12. In a combination key and cylinder lock, a removable key-plate adapted to embrace the case, a cylinder adapted to be rotatably mounted in the case, a hub operated by said cylinder, a sliding latch-bolt, a gravity locking-plate, a lever engaging said latch-bolt and locking-plate and adapted to be engaged by said hub, and means for supporting and releasing said locking-plate, substantially as set forth.

13. In a lock, a removable cylinder rotatably mounted in the lock-case, a hub operated by said cylinder, a lever operated by said hub, a sliding latch-bolt, a gravity-operated locking-plate pivoted to said latch-bolt, means

for raising said locking-plate, and means connecting said lever, latch-bolt and locking-plate whereby the latch-bolt may be retracted 20 as set forth.

14. A lock having its locking parts reversible and invertible, and having reversible and invertible means for supporting and releasing the locking parts, said means being automatically operated by the opening and closing of the door, as set forth.

In testimony whereof I have hereunto set my hand in the presence of two witnesses.

WILLIAM B. MOORE.
